SUPPORTS FOR MOBILE CRANES

Edward B. Nickles and John R. Williams, Manitowoc, Wis., assignors to Manitowoc Engineering Corp., Manitowoc, Wis., a corporation of Wisconsin

Filed July 20, 1956, Ser. No. 599,133

16 Claims. (Cl. 212—145)

This invention relates to improved supports for increasing the stability of mobile cranes and one of the objects of the invention is to provide suitable counterweight structure for the crane which not only enables the crane to lift over the rear portion of a vehicle chassis which supports the mobile crane but also provides sufficient counterweight to assure successful lateral lifting over the side portions of the vehicle chassis.

It is also an object of the present invention to provide an outrigger device for a mobile crane which will adequately support the crane against tipping.

An additional object of this invention is to provide detachable auxiliary means to stiffen the vehicle frame and prevent torsional strains therein without materially increasing the size and, consequently, the weight of the frame members of the vehicle.

A further object of this invention is to provide a support for a crane without increasing the height of the crane mounting.

Further objects and advantages of the invention will be apparent from the following detailed description of a preferred embodiment thereof, as illustrated in the accompanying drawing in which:

Figure 1 shows a truck mounted crane equipped with the present invention, and

Figure 2 is an exploded view of the truck chassis and outrigger.

Referring now to the drawing wherein there is illustrated a truck mounted crane 10 comprising a crane 12, mounted upon a truck chassis 14. The crane 12 includes the usual cab 16, boom 18, boom hoist rigging 20, and hoisting line 22.

Referring now to Figure 2 which shows the truck mounted crane 10 in greater detail, it will be seen that the chassis 14 comprises longitudinal primary support means including generally longitudinally extending frame members 24, and a pair of spaced substantially transversely extending frame members 26 and 28. Intermediate the frame members 26 and 28 there is provided a pair of substantially transversely extending members 30 and 32 which include end portions 34 extending outwardly from the longitudinal members 24 and a center portion 36, extending between the longitudinal members 24. Each of the portions 34 and 36 is securely welded to the longitudinal members 24 to form a rigid framework which defines the primary support structure for the crane 12. Cap bars 40 may be provided to adjust the height of the transverse members 30 and 32 to that of the upper surface 38 of the longitudinal members 24 to insure a uniform supporting surface at a location on the support structure for ring gear 42, on which the crane 12 is mounted.

The end portions of the transverse frame members 26 and 28 are provided with horizontal slots 44 and 46 and with vertical holes to receive mounting pins 48 and 50. The extremities of the end portions 34 of the members 30 and 32 are reduced in cross section for a purpose which will presently appear.

2

There is further provided auxiliary or secondary support means which includes an additional generally longitudinally extending side frame member 52 which includes a rigid beam 54 having connecting links 56 and 58 adjacent its ends. While only one side frame member 52 is shown, it will be understood that a similar side frame will be provided for each side of the truck mounted crane 10. The connecting links 56 and 58 include tongue portions 60 and 62 adapted to fit snugly in the slots 44 and 46 in the frame members 26 and 28. In addition, each of the links 56 and 58 is provided with a slot 64 adapted to receive a flange of the transverse frame members 26 and 28. Vertical holes 66 and 68 are provided in the tongue portions 60 and 62 to receive the mounting pins 48 and 50 to firmly hold the side frame member 52 thereon. In this way the side frame members 52 are readily removably rigidly connected at vertically spaced locations to the adjacent end portions of the transverse frame members 26 and 28. Stirrups 70 and 72 are attached to the beam 54 of the side frame member 52 and are adapted to receive the reduced end portions 34 of the transverse members 30 and 32. The stirrups 70, 72 include internal flat plate members 71 which underlie, and provide a snugly fitting socket for, the reduced end portions 34 of the transverse members 30 and 32. Outrigger feet 74 and 76 are pivotally mounted on the connecting links 56 and 58 of the rigid beam 54 by hinge pins 78 and 80, and are held against rotation by locking pins 82 and 84, inserted in holes provided in flanges on the feet 74 and 76 and in corresponding holes in the connecting links 56 and 58. By withdrawing pins 82 and 84 the feet 74 and 76 may be swung parallel to the longitudinal axis of the truck mounted crane 10 and locked in that position by placing the locking pins 82 and 84 in alternate holes 86 and 88, thus providing a retracted traveling position. It will be understood that with the side chassis 14 secured in place the members form the integrated rigid framework which supports the crane 12, and that the auxiliary support means supports the end portions 34 of the transverse members 30 and 32 through the stirrups 70 and 72 carried by the beam 54 of the frame members 52 in a manner which will prevent any torsional strain on the longitudinal members 24 during the time when the crane 12 is lifting a load from the side of the truck. Further, as illustrated more clearly in Figure 1, the integrated rigid framework may be ground supported by providing suitable blocking 92, 94 under the outrigger feet 74 and 76 which are carried by the side frame members 52.

Boom stop cables 96 permit the boom 18 to be raised almost vertically without danger of tipping over backwards whereby the hoisting line 22 may be engaged in a lifting ring 90 provided on the side frame members 52 so that the crane 12 may be used to remove its own side frame members 52 to conveniently reduce the weight of the vehicle for highway travel.

While a preferred embodiment has been described, it is to be understood that the invention is capable of other forms and is to be limited only by the scope of the appended claims.

Having thus described our invention we claim:

1. A mobile support for a crane comprising a vehicle chassis, said chassis including a pair of longitudinal frame members, a pair of spaced transverse frame members secured to and extending laterally beyond said longitudinal members, at least one intermediate transverse frame member having a center portion lying between said longitudinal members and end portions extending laterally beyond said longitudinal members, said longitudinal and intermediate transverse members being secured together to form an integrated frame, the top surfaces of said longitudinal and intermediate transverse members lying

in a common plane, a crane supporting ring mounted on said longitudinal and intermediate transverse members, and longitudinal side frames removably connected to the ends of said transverse members, said side frames including supporting outrigger feet located at points spaced longitudinally from said transverse beam lying in said plane.

2. A support for a crane as defined in claim 1 wherein said outrigger feet are pivotally mounted on a vertical axis.

3. A mobile crane unit including a crane rotatably supported by a chassis structure, said chassis structure being formed from interconnected frame members which define a location on which said crane is rotatably mounted, said frame members being of adequate strength to support the dead weight load of said crane during movement of said unit while being of inadequate strength to support the full working load thereof, and demountable side frames attached to the ends of certain of said frame members along each side of said chassis structure to increase the strength of said location to enable said chassis structure to support the full working load of the crane, said side frames each being provided with outrigger elements for resting engagement with supporting surfaces to distribute a portion of the working load of said crane thereto.

4. A mobile crane unit including a crane rotatably supported by a mobile chassis structure, said chassis structure being formed from interconnected frame members which define a central location on which said crane is rotatably mounted, said frame members being of adequate strength to support the dead weight load of said crane during generally horizontal movement of said unit while being of inadequate strength to support the full working load thereof, and demountable side frames attached to the ends of the frame members defining said location along each side of said chassis structure to increase the strength of said chassis structure to enable the same to support the full working load of said crane, said side frames each being provided with outwardly swingable elements for resting engagement with supporting surfaces to distribute a portion of the working load of said crane thereto.

5. A mobile crane unit including a crane rotatably supported by a mobile chassis structure, said chassis structure including a frame defining a location on which said crane is rotatably mounted, said frame being of adequate strength to support the dead weight load of said crane during movement of said unit while being of inadequate strength to support the full working load thereof, and demountable side frames attached to opposite sides of said frame to increase the strength of said location to enable said chassis structure to support the full working load of said crane, said side frames each being provided with outrigger elements for resting engagement with supporting surfaces to distribute a portion of the working load of said crane thereto.

6. In combination, a crane and support structure having a ring rotatably mounted the crane thereon, said support structure comprising a plurality of generally longitudinally and transversely extending beams interconnected to define a frame, said longitudinal beams and at least one of the transverse beams underlying and supporting the ring, said transverse beams extending outwardly from adjacent said ring and terminating in end portions disposed beyond the longitudinal beams, an additional longitudinal member disposed along opposite sides of said frame in outwardly spaced relationship relative to the adjacent longitudinal beam, and connectors for readily removably connecting the additional longitudinal members at spaced locations to the adjacent end portions of each of the transverse beams to define a substantial auxiliary support therefor.

7. The support structure for a crane as set forth in claim 6 wherein said additional longitudinal members in-

clude ground supported outrigger feet located at points spaced longitudinally from said transverse beam underlying said ring.

8. A mobile crane assembly comprising, in combination, a crane and support structure therefor, said support structure including a vehicle chassis having elongated interconnected generally longitudinally and transversely extending frame members, the upper surfaces of said longitudinal frame members and at least one of said transverse frame members lying in a common plane, a ring disposed above said plane and secured to the frame members disposed therein for supporting the crane, said transverse frame members extending outwardly relative to the longitudinal frame members and terminating in end portions disposed in outwardly spaced relationship relative thereto, an additional generally longitudinally disposed member extending along opposite sides of said chassis between the adjacent end portions of the transverse members in outwardly spaced relationship to the adjacent longitudinal frame member, and connectors for readily rigidly removably connecting the additional longitudinal members at vertically spaced locations to the adjacent end portions of each of the transverse frame members to define a substantial auxiliary support therefor.

9. The mobile crane assembly as set forth in claim 8 wherein said additional longitudinal members include ground supported outrigger feet located at points spaced longitudinally from said transverse member lying in said plane.

10. Structure for supporting a crane at a location thereon, said structure including interconnected generally longitudinally and substantially transversely extending elongated frame members disposed in underlying relationship relative to the location, an additional generally longitudinally extending elongated member disposed along opposite sides of said structure in spaced relationship to the location and the adjacent longitudinally extending frame member, and connectors for readily removably connecting the additional members at spaced locations to the adjacent end portions of each of the transversely extending frame members to define a substantial auxiliary support means therefor.

11. The structure for supporting a crane as set forth in claim 10 together with ground engaging outrigger support means carried by said additional members.

12. Mobile structure for supporting a crane assembly at a location thereon, said structure including generally longitudinally extending elongated frame members, a plurality of substantially transversely extending elongated frame members interconnected with the longitudinally extending frame members, said longitudinally and at least one of the transversely extending frame members being disposed in underlying relationship relative to the crane supporting location, an additional generally longitudinally extending elongated member disposed along opposite sides of said structure in outwardly spaced relationship to the crane supporting location and the adjacent longitudinally extending frame member, and connectors for readily removably rigidly connecting the additional members at spaced locations to the end portions of each of the adjacent transversely extending frame members to define a substantial auxiliary support therefor.

13. The mobile structure for supporting a crane assembly as set forth in claim 12 together with ground engaging outrigger supports carried by said additional members at positions thereon which are longitudinally spaced from the said underlying transversely extending frame member.

14. The mobile structure for supporting a crane assembly as set forth in claim 12 wherein said location is defined by a ring-like member.

15. Structure for supporting a crane at a location thereon, said structure comprising a frame including spaced apart generally laterally outwardly extending frame members, said frame being of adequate strength to support

the dead weight load of a crane while being of inadequate strength to support a working load thereof, a demountable side frame member disposed along opposite sides of the frame in spaced relationship thereto, and connectors for readily removably attaching the side frame members at spaced locations to each of the generally laterally outwardly extending frame members to substantially increase the strength of the location on the structure to enable the frame to support a working load of a crane.

16. A mobile crane assembly including a crane and structure for supporting the crane, said structure including a chassis having a location thereon whereat said crane is rotatably mounted, said chassis comprising a frame including spaced apart generally laterally outwardly extending frame members, said frame being of adequate strength to support the dead weight load of said crane during movement of said assembly while being of inadequate strength to support a working load thereof, a demountable side frame member disposed along opposite sides of the frame in spaced relationship thereto, 15 20

and connectors for readily removably attaching the side frame members at spaced locations to adjacent end portions of each of the generally laterally outwardly extending frame members to increase the strength of said location to enable the frame to support a working load of the crane.
